UNITED STATES PATENT OFFICE.

FREDERICK C. JAENEKE, OF MILWAUKEE, WISCONSIN.

WATER-HEATER.

1,020,558.

Specification of Letters Patent. Patented Mar. 19, 1912.

Application filed September 28, 1911. Serial No. 651,744.

To all whom it may concern:

Be it known that I, FREDERICK C. JAENEKE, a citizen of the United States, and resident of Milwaukee, in the county of Milwaukee and State of Wisconsin, have invented certain new and useful Improvements in Water-Heaters; and I do hereby declare that the following is a full, clear, and exact description thereof.

My invention consists in what is herein particularly set forth with reference to the accompanying drawings and pointed out in the claims of this specification, its object being to provide simple, economical and efficient water-heaters for hot water heating systems, as well as to economize fuel and the labor of feeding the same to the fire-pots of said heaters.

Figure 1 of the drawings represents a vertical section view of a water-heater constructed in accordance with my invention, the plane of the section being indicated by line 1—1 in Figs. 4, 5 and 6; Fig. 2, a similar view on the plane indicated by line 2—2 in Fig. 5; Fig. 3, a plan view of the heater with the smoke-flue of the same in horizontal section, and Figs. 4, 5 and 6, horizontal section views of said heater on planes respectively indicated by lines 4—4, 5—5 and 6—6 in Fig. 2.

Referring by numerals to the drawings, 7, 8, 9, 10 and 11 indicate a series of sections embodied in a cylindrical base-burner water-heater of my invention, these sections being cast with reference to stacking of the same one upon another in fluid-tight spigot-joint union. The sections 7, 8, 9 and 10 are provided with outer registering ears 12 for the engagement of bolt-rods 13 upon which 40 to run clamp-nuts, whereby said sections of the heater are firmly held together. The upper heater section is cast with an upwardly extending central cylindrical extension 7' in which a cylindrical fuel-magazine 45 14 is suspended. As a matter of detail the fuel-magazine is provided with an upper outer flange 14' that rests upon an inner upper flange 7'' of the extension 7' of the heater section 7, and bolted to ears 7''' of 50 said extension is a centrally apertured top plate 15 having a door 16 in hinge connection therewith to close said aperture and the fuel-magazine.

Rigidly secured within the heater-section 55 7, by any suitable means, is a circular par-

tion 17 that surrounds the fuel-magazine and rests upon the top of the heater-section 8 to which it may be also rigidly secured by any suitable means, and thus a water-chamber is provided in said heater-section 7. 60 Communicating with the water-chamber aforesaid are vertical water-channels 18 between inner and outer walls of the heater-section 8, and these channels also communicate, through ports 19, with a water-chamber in the heater section 9. The heater section 7 is provided with a nipple 20 with which to couple a hot water ejection pipe 21, and the heater section 9 is provided with a nipple 22 with which to couple a cold 70 water induction pipe 23. The heater-section 8 contains a fire-pot 24 in register with the aforesaid fuel-magazine, the bottom of the fire-pot being a pivotally movable grate 25, as herein shown, or any other suitable form 75 of grate over an ashpit 26 in said heater-section, an opening to the ashpit being closed by a suitable door 27, as is common practice in heaters of various kinds. The fire-chamber has an outlet 28 to a smoke-box 80 extension 8' of the heater-section 8, and a cutoff 29 is provided for said outlet. Ports of the fire chamber are open to vertical ducts 30 between the inner and outer walls of the heater-section 8, and these ducts communicate 85 with branches of a Y-shaped smoke-trunk 32 in the heater-section 9, the stem of this trunk being provided with a spout 33 leading into a base-chamber 34 of the heater formed by the sections 10 and 11 of the 90 same.

The heater is provided with a flue 35 connecting its base-chamber 34 and smoke-box 8', and a check-draft opening 36 in the flue is controlled by a crank-controlled sliding damper 37. The heater-section 8 has a fuel inlet 38 for which a door 39 is provided, and the heater-section 10 has a clean-out opening normally closed by a door 40. The heater-section 8 is shown provided with 100 nipples 41 with which to connect a heating coil of domestic hot-water tank if desired, otherwise these nipples are closed by means of plugs 42.

From the foregoing it will be understood 105 that the heater is similar to a base-burner stove having a magazine from which fuel is automatically fed to the fire-pot, and that provision is had for circulating water above the fire-chamber, alongside the same and 110

the ashpit, vertically of the same, and about the smoke-trunk between said ashpit and the base-compartment of said heater, whereby the water is exposed to a great amount of heat radiating surface and thus economically raised to a circulating temperature.

I claim:

1. A water-heater having a smoke-trunk therein below the ashpit thereof in communication with a base-compartment that is open to a draft-flue, there being ducts leading from the fire-chamber of the heater to the smoke-trunk, and water circulating space above said fire-chamber, around the same and said ashpit, and about said smoke-trunk.
2. A water-heater provided with an upper fuel-magazine and having a smoke-trunk therein below the ashpit thereof in communication with a base-compartment that is open to a draft-flue, there being ducts leading from the fire-chamber of the heater to the smoke-trunk, and water circulating space above said fire-chamber, around the same and said ashpit, and about said smoke-trunk.
3. A water-heater having a fire-chamber, ashpit and draft-flue section provided with vertical channels and ducts between walls thereof; a base-compartment of the heater open to the draft-flue, a smoke-trunk under the ashpit open to said ducts and base-compartment, said channels being open to space about the smoke-trunk; and an upper water-

chamber section in communication with said channels.

4. A water-heater having a fire-chamber, ashpit and draft-flue section provided with vertical channels and ducts between walls thereof; a base-compartment of the heater open to the draft-flue, a smoke-trunk under the ashpit open to said ducts and base-compartment, said channels being open to space about the smoke-trunk; an upper water-chamber section in communication with said channels, and a fuel-magazine suspended within an upward extension of said water-chamber section.

5. A water-heater having a fire-chamber, ashpit and draft-flue section provided with vertical channels and ducts between walls thereof; a base-compartment of the heater open to the draft-flue, a Y-shaped smoke-trunk under the ashpit having its branches open to said ducts and its stem open to the base-compartment, said channels being open to space about the smoke-trunk; and an upper water-chamber section in communication with said chamber.

In testimony that I claim the foregoing I have hereunto set my hand at Milwaukee in the county of Milwaukee and State of Wisconsin in the presence of two witnesses.

FREDERICK C. JAENEKE.
